UNITED STATES PATENT OFFICE

ALFRED FALLOT, DECEASED, LATE OF PLÄUEN I. VOGTL, GERMANY, BY HARRY PRIESTER, EXECUTOR, OF BERLIN, GERMANY

MEANS FOR RAISING, CHANGING, AND DRIVING THE PAPER-WEB ROLLS IN PRINTING MACHINES, AND MORE PARTICULARLY IN ROTARY PRINTING MACHINES

Application filed November 9, 1925, Serial No. 68,006, and in Germany November 22, 1924.

This invention relates to improvements in means for raising, changing and driving the paper web rolls in printing machines and more particularly in rotary printing machines.

In rotary printing machines the raising and changing of the paper webs is a troublesome and arduous job and in order to relieve the attendants and to make the working simpler, it has been suggested to transfer the used up roll to an auxiliary carrier or support, but in such a case the heavy, new, roll must first be raised into the stationary bearings so that the machine does not run out of paper web. It is not adequate to provide a winch or some such raising means without at the same time passing the nearly run out web to the auxiliary bearings to continue feeding to the printing machine without stoppage whilst the main web support is liberated to receive the new or fresh roll of paper which can be hoisted into the main web support by mechanical means.

The invention solves the problem as thus stated and does so by means of a device in which the web changing is effected whilst the paper guiding and the web feed are of an ordinary type and as far as possible remain unaltered in design, the new web can be inserted during ordinary operation; the used up web or roll can be ejected without stoppage and tearing and unequal or irregular unwinding of the web is avoided. It is to be noticed that the feeding of the web is rendered irregular by the fact that the rolls are not accurately circular and also the diameter of the roll decreases as the paper is fed off so that special means have to be provided to ensure uniformity of feed. The ejection of the used up roll and the severing of the paper web can also be carried out without interrupting the operation of the printing machine.

It has already been proposed to effect the feeding movement of the web roll in rotary printing machines by means of an endless band which contacts frictionally with the roll. The drive for the endless band is, according to this invention, used for regulating the unwinding of the roll and at the same time

for carrying out the mechanical changing of the web roll.

The invention is illustrated by way of example in some typical forms in the accompanying drawings in which:

Fig. 1 is a side view of a web feeding, ejecting and changing device according to this invention.

Fig. 2 is a partial front elevation in which the transfer bearer for the ejector is only indicated as regards position.

Fig. 3 is a sectional elevation of the ejector of Fig. 1.

Fig. 4 is a side elevation illustrating the operations of transferring and ejecting.

Fig. 5 shows a modified form of web feed.

Fig. 6 is an end view of a modified form of paper web feed with automatic regulation of the drive as the feeding proceeds.

Fig. 7 is a side elevation in section through the centre plane of Fig. 6 and looking on the left hand upright.

Fig. 8 is a section similar to Fig. 7 looking on the right hand upright.

Fig. 9-Fig. 9^d show details of the main adjustable supports for the web with chain drive.

Fig. 10 shows a modified form of the invention as applied to a machine with horizontal supporting rails for the paper web.

In carrying the invention into effect according to the form shown in Figs. 1, 2, the paper web is carried in the usual manner by a spindle *p* and is supported by two vertical uprights *s*. The bearings *d* for the spindle *p* are carried by threaded shafts *r* rotatably mounted in the uprights *s* on which the bearings are slidably supported. The bearings *d* rise and fall with the rotation of the threaded shafts *r* and are fitted with ball bearings so as to ensure easy rotation of the web roll spindle *p*. The threaded shafts are rotated through the bevel gears *r*¹ on the shaft *f*, which may be operated either by hand (see Fig. 2) or by the motor *m* (Figs. 2 and 6). The bearings *d* are arranged so that they can raise the spindle *p* of the paper web so high that the web can be freely unrolled, as shown in Figs. 1, 2. In the form shown in Figs. 1 and 2, an endless band *u* is arranged at an angle to the

55

60

65

80

85

90

95

100

line of lift of the bearers d and the paper web is brought into contact with this band so that the movement of the band is transmitted to the paper web in a manner hereinafter described. As the paper web unrolls and becomes reduced in diameter, the roll may be raised by the bearers d so that the web is kept in contact with the band u . When the paper roll has been nearly used up, and it becomes necessary to insert a fresh roll, the bearers d have raised the nearly exhausted roll by means of the motor m , or the roll may be raised as and when required by the said motor, sufficiently high until the ends of the spindle p reach a position where they come under the transfer bearers which are located at each side of the machine and co-act with the spindle p in the manner described below.

The transfer bearers each comprise a slideable supporting arm a (Figs. 1 and 4) which at the end facing the upright s has an open topped bearing. The top edge of the carrier arm in each case is formed with rack teeth and has side projecting ledges which slide in suitable guides in the machine frame. The uprights s on each side have a bracket b and two guide webs w , which latter form the guide slides and supports for the slideable carrying arm a , as can best be seen in the sectional view Fig. 3. A spring a^1 , fixed at one end, the right hand in Fig. 1, to the machine frame and at the other to the carrying arm tends to hold this carrying or transfer arm in the position shown in Fig. 1. At the bearing end of the transfer arm, an inclined face is formed at a^2 on the bottom thereof and directly under the open topped bearing in which the spindle p of the roll to be ejected may be placed for purposes of transferring (Fig. 4). The open top of the bearing is so arranged and formed that the spindle p cannot fall out after having been deposited therein. As the lifting bearers d are raised, the spindle p in rising first pushes back the transfer arms a against the action of their springs until the spindle p has been raised to a position over the open top of the bearing of the transfer arm a , whereupon the arm a springs back under the action of its spring a^1 and the bearing of the transfer arm is then under the spindle p . When the lifting bearers d are now lowered, the spindle p remains behind in the transfer bearers a and the fresh paper web can be inserted in the bearers d when these reach their lower position.

Side cheeks b are formed on or fixed to the machine frame so that they lie outside the transfer arms with respect to the central plane of the machine. These cheeks have inwardly projecting lips or ledges b^1 which are curled up at the outer end of the bracket formed by the said cheeks so as to act as a bearing support for the ejected web spindle, see Fig. 1. A toothed wheel or segment c is keyed to a shaft c^2 supported in the cheeks b and guide

webs w , and this toothed wheel meshes with the rack teeth formed on the transfer arm a . A lever c^1 is provided for operating the toothed wheel or segment c . A stop n on the cheek b is located to allow the transfer arm to pass freely when it is drawn back by the lever c^1 but intercepts the spindle p resting in the bearings of the transfer arms. At a point above the lever c^1 , there is pivoted a bell crank lever one arm of which acts as a cutting lever to support a knife over the web whilst the other arm g carries a roller engaging a cam formed on or fixed to the shaft c^2 . The severing lever g is mounted on a shaft f . The operating cam e for the severing lever g is rotated to operate the severing lever at the time of operating the transfer arm a . The bell crank lever is acted upon by a spring g^1 which tends to keep the roller of the lever against the cam e (Fig. 1). Two such severing levers are provided one on each side of the machine and the severing knife is thus supported at each of its ends across the machine, so as to cut the paper web from the ejected roll.

The endless band u is arranged at an inclination to the line of lifting of the lifting bearers d . This band passes over two rollers k , the upper one of which is mounted on the shaft f^3 whilst the lower one is mounted in slideable bearings for the purpose of imparting tension and is driven at the speed of feeding required for the machine. A band such as the band u may be used for applying a braking action to badly balanced or eccentric rolls but, as here described, it may also be used effectively as the drive for the web, so as to secure uniformity of feed.

When a fresh web has been inserted in the bearers d , these are raised until the roll comes into contact with the endless band u , whereupon the roll is caused to rotate. The paper web is threaded over the guide rollers in the printing machine and work proceeds. As the paper web is unwound and the diameter of the roll decreases the bearers d are raised and the roll kept in frictional contact with the band u to be driven thereby. When the spindle of the roll reaches the upper position shown in Figs. 1 and 4, it pushes the bottom inclined face a^2 and thereby moves the transfer arm a to the left in Figs. 1 and 4, until the spindle is over the open topped bearing. The spring a^1 then causes the transfer arm a to return and the bearings of the transfer bearer receive the spindle p . The bearers d are now lowered, and a new roll inserted therein. When the freshly inserted roll has been raised so as to contact with the endless band u , the web is reeled off and by a gumming strip the fresh web is joined to the old web and thereafter the expended roll which is in the transfer bearer arms a is ejected and the web of paper severed from the roll by the action of the severing knife. For this purpose the

130

lever c^1 is operated to rotate the toothed member c whereby the transfer arms a with the expended paper roll are pushed backwards. The spindle p of the ejected roll is tripped up by the stop n , whereby the said spindle is taken out of the transfer bearings and the ejected roll falls on to the ledge b^1 and rolls to left in Fig. 1 to the position indicated by the reference letter b^1 in this figure. During the rotation of the toothed member c the roller arm of the bell crank lever g comes opposite the dip in the cam e , as can be seen in Fig. 1 and under the action of the spring g^1 , the lever g snaps round in a clockwise direction in Fig. 1 so that the severing knife severs the expended web from its roll. On returning the lever c^1 the transfer arm a is returned and the bell crank lever g and the other parts operated therewith are also returned to their initial positions, under the action of the spring g^1 . All the parts are then in order for the reception and feeding of the fresh paper web and these operations are repeated each time a web requires to be changed.

The web can thus be changed, without stoppage of the machine, by a single workman. The removal of the ejected roll and the introduction of the fresh roll can be effected single handed by one and the same workman without stopping the machine.

In Fig. 5, the invention is illustrated as applied to a machine for simultaneously printing several webs supported in bearers at different heights. The operation of the upper web changing transfer arm is shown as being effected by a lever c^3 located in an easily accessible position and articulated to the lever c^1 of the upper transfer arm. Otherwise the mechanism is, as will be readily understood, merely a duplication of the mechanism described with reference to Fig. 1. It will be understood that the constructional details of the transfer arm and the ejector mechanism may be varied without departing from this invention.

In the form of the invention illustrated in Figures 6-10 the web feed and changing mechanism is provided with automatic regulation means for controlling the drive as the web unwinds—the operation being effected by electric power.

In front of the rotary printing machine, there are arranged, as in the first described form, the uprights s which carry the vertical threaded shafts r . These uprights have guides for the slideable lifting bearers d which are threaded on the shafts r so as to be raised or lowered by the rotation of these shafts. The left hand upright (Fig. 6) has means for adjusting the position of the web sideways in the bearers d . The threaded shafts r are provided with worm wheels r^1 at their upper ends, which worm wheels engage with worm threads on the transverse shaft f , which is driven by the electric motor m . A switch

board h is supported on the upright and is arranged to control the direction of rotation of the traverse shafts r so as to raise or lower the bearers d as required. On the motor shaft f there is a coupling f^1 which is controlled by a magnet or solenoid f^2 . When current passes to the motor m the solenoid f^2 is also energized and thereby the fork f^3 of the clutch is operated to throw the clutch out of operation. When no current passes to the motor m and consequently the solenoid remains unenergized the coupling f^1 is thrown into engagement under the action of its spring and the chain drive hereinafter described becomes operative. The two lifting bearers d may thus be raised or lowered by the rotation of the shaft f which may be effected either by the motor m as described or by the chain gear hereinafter described and operating through the coupling f^1 . Only one of these means can however operate at any given time.

Above the bearers d and mounted in the standards s , the transfer bearers are arranged. These have arms a with open topped bearings as can be seen in Figs. 7 and 8 and are acted upon by springs a^1 which hold these arms pressed forward into the path of the rising roll of paper. As in the first described form the bottom face of the transfer arm is inclined so that on contacting with the rising spindle the arm is caused to slide against the action of its spring and when the spindle has been raised sufficiently the transfer arms spring or snap back to take the spindle p in the open topped bearings and leave the main lifting bearers free to be moved down without interference.

Over the transfer bearer a there is arranged a switch lever h^1 which is controlled by the rising movement of the bearer d by engaging a striker bar h^2 arranged on the left hand bearer d (Fig. 6). In this way the motor m is controlled so as to rotate the shafts r in the opposite direction and to lower the bearers d . In a similar manner a switch lever h^1 at the foot of the upright s is operated by a striker h^3 on the sinking bearer d to cut out the motor when the bearers are in position to receive a fresh roll.

As in the first described form the web drive is effected by means of an endless band u which is guided over two rollers k , k^1 . The roller k^1 is supported at the base of the uprights and is driven at the speed of operation of the printing machine, whilst the roller k is mounted in bearings slideable in slots k^2 in the machine frame to tension the band u . This tensioning is conveniently effected by means of a weighted lever k^3 , which tends to move the bearings upwards in the slots k^2 and thereby stretch the band. The band u is so arranged with respect to the bearers d and the transfer bearer arm a that the band u can operate simultaneously on the roll about

to be ejected and on the freshly inserted roll. The paper rolls themselves are carried by the usual spindles p which rotate in ball or roller bearings in the bearers d .

As the diameter of the paper roll is reduced as the paper web is unwound, the drive effected through the endless band would eventually cease and it therefore becomes necessary to compensate for the diminishing diameter of the roll. Such compensation could be effected by hand, as for instance by switching on the motor m when the paper web had unwound sufficiently far and by raising the roll again bring it into effective operative contact with the band u , the motor being shut off when the adequate contact pressure between the roll and the band had been attained. Such a method would necessitate continual observation of the paper roll and continual switching off and on of the motor. From experience it has been found that the operator moves the roll up in a jerky manner and stretches the band as far as possible so as to reduce the frequency with which the raising operation has to be performed. The feed is therefore irregular and frequently results in the rupture of the web in consequence of an abruptly applied frictional contact between the web and the band u . Even with careful control and watching, it would be impossible to obtain a raising movement of the roll by hand in strict accordance with the unwinding movement of the web.

According to this invention the paper roll drive and raising mechanism are arranged to co-operate so that the drive is automatically regulated as the paper web is unwound. As the paper is unwound, the diameter of the roll diminishes and in proportion as this diameter diminishes so must the relation of the roll to the driving band be altered.

In order to effect this compensating adjustment a chain drive, illustrated in Figs. 6-9^a, is introduced at the side of one of the uprights s . A broad pinion o^1 is provided on the spindle p or the teeth may be cut out of the spindle itself and this pinion is constantly in mesh with a toothed wheel o^2 which drives a chain wheel o^3 mounted on the same shaft therewith. This chain wheel engages a chain o which also passes over the chain wheels o^4 (Figs. 6 and 8) and thereby transmits a rotating movement to the toothed wheel o^5 and the coupling f^1 . Through the coupling f^1 , when it is in engagement with the shaft f , the rotation of the paper roll spindle p is thus transmitted to the shaft f , worm wheels r^1 and the threaded traverse spindles r which on rotation raise the paper roll by an amount depending upon the rate at which the paper web is being unwound from the roll.

As the paper rolls are not always uniformly wound and as it is also necessary to adjust their position sidewise so as to secure proper

registering, the device shown more fully in Figs. 9^b-9^d is provided. On the left hand upright s a horizontal threaded spindle i is mounted in a casing i^1 and this spindle can be rotated by a handwheel i^2 . By these means a stirrup i^3 mounted on the spindle i and engaging in a collar on the paper roll spindle p may be moved inwards or outwards to effect sidewise adjustment of the web. Springs, as indicated on the drawing, press the stirrup upward into the collar on the spindle p . After adjustment in the manner described the spindle p can be locked so as to prevent displacement, as for instance by a tongue t (Fig. 6) engaging in grooves t^1 on the spindle.

In order to give resilience to the chain drive between the chain wheel o^3 , toothed wheel o^2 and the toothed wheel o^1 , the toothed wheel o^1 and the chain wheel o^3 are supported in a bearing carried on springs as indicated at o^6 in Figs. 9 and 9^a. By this means the drive yields to sudden shocks and thereby avoids breakages.

The operation of the device described for raising and changing the paper web, as well as for feeding the web to the machine, is as follows:

When a roll has to be inserted in the bearers d in the uprights s and the bearers have been lowered to their bottom positions, the roll is inserted and set in the correct central position by means of the hand wheel i^2 . The switch h is then operated and current supplied to the motor m and the solenoid f^2 so that the coupling f^1 is thrown out of engagement and the bearers d and the roll are raised until the roll comes into driving contact with the band u whereupon the motor m and the solenoid or magnet f^2 are switched off and the coupling f^1 automatically comes into engagement with the shaft f so that the chain drive through the toothed wheel o^1 on the roll spindle p becomes operative.

The movement of the band is transmitted to the roll and when the expended roll has been passed to the transfer bearers and a fresh roll inserted in the main lifting bearers d , this fresh roll soon acquires the speed of feed of the machine and is gummed to the web passing from the expended roll. At the same time the web from the expended roll is severed. By the rotation of the roll spindle p , the toothed wheel o^1 drives the gear wheel o^2 and chain wheel o^3 , whereby the chain o , chain wheel o^4 , toothed wheel o^5 , and coupling f^1 and shaft f are driven so as to rotate the screwed shafts r which raise the bearers d . The traverse screw shafts r raise the bearers in direct proportion to the drive imparted to the chain o by the unwinding paper roll so that the roll always remains in proper driving contact with the driving band u . When the partially expended roll has been raised to the height of the transfer arm a ,

this arm is pushed back and the upward movement of the bearers *d* continues until the transfer arm again springs under the spindle *p* and receives the said spindle in its journals. The striker *h*² then operates the switch lever *h*¹ and starts up the motor *m* so that the bearers *d* are lowered. The spindle *p* remains behind in the transfer bearers whilst the main bearers *d* are lowered to their bottom position. The chain drive (*o*-*o*⁵) does not participate in the drive of the shaft *r* in consequence of the coupling *f*¹ being thrown out, as described above, when current is supplied to the motor *m* and solenoid or magnet *f*². When the striker *h*³ on the bearer *d* operates the lower switch lever *h*⁴, the motor *m* and magnet *f*² are cut out. The regulation of the reversible motor *m* may be effected from any desired point so as to modify according to requirements the frictional contact between the band *u* and the roll by raising or lowering the latter.

The same principles may be applied to the automatic feeding and progressive movement 25 of paper rolls which are mounted on horizontal or other inclined rails as is illustrated diagrammatically in Fig. 10.

The bearers *d* for the paper roll are traversed by the threaded shafts *r*. The transfer 30 bearers in the arms *a*, which are operated on by springs *a*¹ take up the spindle from the main bearers *d* and retain this spindle *p* when the main bearers *d* are retracted. In this 35 form also the roll is driven by an endless band and as the paper web is unwound from the roll, the threaded rods *r* are rotated by suitable mechanism, such as a chain drive and the main bearers engaging said threaded rods are fed forward to maintain the contact of the 40 paper roll with the endless band in a manner to ensure uniform tensioning as in the above described modifications.

In order to prevent excessive tensioning of the band *u*, a weighted lever is provided as in 45 the previous form so that the band can yield by causing the lever to lift when any excessive tension is applied.

In place of an endless band other frictional 50 driving means may be used, as for instance some form of cam drive may be provided in which frictional discs transmit the rotation to the paper roll and as the diameter of the roll diminishes and the roller is raised, these discs may by means of a cam guide, be caused 55 to approach the circumference of the diminished diameter, and be raised in company with the roll, in a ratio determined by the reduction of the diameter and the traverse of the roll.

60 What is claimed is:

1. A device for lifting and changing paper rolls in rotary and other printing machines which print from the roll having lifting bearers to hoist the paper roll and to enable it to 65 rotate freely and auxiliary bearers adapted

to be automatically moved out of the path of the paper roll spindle on the forward traverse movement of the lifting bearers and after the lifting bearers have passed to automatically return into their original position and to pick up the paper roll spindle on the return movement of the said lifting bearers. 70

2. A device for lifting and changing paper rolls in rotary and other printing machines which print from the roll having lifting bearers to hoist the paper roll substantially vertically and to enable it to rotate freely and auxiliary bearers arranged to pick the paper roll spindle from the said lifting bearers which are mounted slidably transversely to the line 80 of traverse of the lifting bearers so that they can automatically be pushed out of the path of the spindle roll when the said spindle is being raised in the lifting bearers.

3. A device for lifting and changing paper rolls in rotary and other printing machines which print from the roll having lifting bearers to hoist the paper roll substantially vertically and to enable it to rotate freely and auxiliary bearers arranged at the upper part of 90 the frame of the device in such a manner that they may be pushed out of their normal position and allow the paper roll spindle to pass, but on the return movement of the lifting bearers pick the paper roll spindle from the 95 said bearers.

4. A device for lifting and changing paper rolls in rotary and other printing machines which print from the roll, comprising in combination, auxiliary bearers pivotally arranged at the upper part of the device and serving for taking up the spindle of the paper roll, lifting bearers for taking up a fresh paper roll, means for moving the lifting bearers substantially vertically into the proximity 100 of the auxiliary bearers and for bringing the said spindle into engagement with the said bearers.

5. A device for lifting and changing paper rolls in rotary and other printing machines which print from the roll, comprising in combination, auxiliary bearers pivotally arranged at the upper part of the frame of the device and serving for taking up the spindle of the roll to be printed, lifting bearers for taking up a fresh paper roll, means for moving the lifting bearers substantially vertically into the proximity of the auxiliary bearers, the said spindle being brought into engagement with the auxiliary bearers and other means for rotating the roll in the lifting bearers. 115 120

6. A device for lifting and changing paper rolls in rotary and other printing machines which print from the roll, comprising in combination, auxiliary bearers pivotally arranged at the upper part of the device and serving for taking up the spindle of the roll to be printed, lifting bearers for taking up a fresh 125 130

roll, means for moving the lifting bearers substantially vertically into the proximity of the auxiliary bearers, the said spindle being brought into engagement with the auxiliary bearers and a device for rotating the roll resting in the auxiliary bearers and the roll resting in the substantially vertically movable lifting bearers.

7. A device for lifting and changing paper rolls in rotary and other printing machines which print from the roll, comprising in combination, auxiliary bearers pivotally arranged at the upper part of the device and serving for taking up the spindle of the roll to be printed, lifting bearers for taking up a fresh paper roll, means for moving the lifting bearers substantially vertically into the proximity of the auxiliary bearers, the said spindle being brought into engagement with the auxiliary bearers and a fractional device for rotating the roll resting in the auxiliary bearers and the roll resting in the substantially vertically movable lifting bearers during its movement towards the auxiliary bearers.

8. A device for lifting and changing paper rolls in rotary and other printing machines which print from the roll, comprising in combination, auxiliary bearers for taking up the spindle of the roll to be printed, lifting bearers for taking up a fresh paper roll, means for moving the lifting bearers into the proximity of the auxiliary bearers, other means enabling the said auxiliary bearers to automatically take up the spindle of the said fresh roll when lifted and nearly unwound, the said spindle being brought into engagement with the auxiliary bearers, a frictional device for rotating the roll resting in the auxiliary bearers and the roll resting in the lifting bearers during its movement towards the auxiliary bearers and an apparatus for ejecting the expended roll in the auxiliary bearers preliminary to the spindle of the fresh roll being brought into contact with the said auxiliary bearers.

9. A device for lifting and changing paper rolls in rotary and other printing machines which print from the roll, comprising in combination, auxiliary bearers for taking up the spindle of the roll to be printed, lifting bearers for taking up a fresh paper roll, means for moving the transport bearers into the proximity of the auxiliary bearers, the said spindle being brought into engagement with the auxiliary bearers, a frictional device for rotating the roll resting in the auxiliary bearers and the roll resting in the lifting bearers during its movement towards the auxiliary bearers, and an automatically operated apparatus for sliding the auxiliary bearers transversely to the line of movement of the lifting bearers in order to eject the unwound roll preliminary to the fresh roll being brought into contact with the auxiliary bearers.

10. A device for lifting and changing paper rolls in rotary and other printing machines which print from the roll, comprising in combination, auxiliary bearers for taking up the spindle of the roll to be printed, lifting and transport bearers for taking up a fresh roll, means for moving these lifting bearers into the proximity of the auxiliary bearers, bearing surfaces on the said auxiliary bearers, a frictional device for rotating the roll resting in the auxiliary bearers and the roll resting in the lifting bearers during its movement towards the auxiliary bearers, an apparatus for ejecting the expended roll in the auxiliary bearers preliminary to the spindle of the fresh roll being brought into contact with the said auxiliary bearers, said auxiliary bearers being adapted to be pressed yieldingly backward when being engaged by the spindle of the fresh roll and to be pressed forward after the said spindle has passed the free ends of the said lifting bearers, thereby bringing the bearing surface of the last mentioned bearers into engagement with the said spindle.

11. A device for lifting and changing paper rolls in rotary and other printing machines which print from the roll, comprising in combination, auxiliary bearers for taking up the spindle of the roll to be printed, lifting bearers for taking up a fresh paper roll, a device for ejecting the unwound roll, an electric motor for moving the lifting bearers into the proximity of the auxiliary bearers in order to deposit the spindle of the fresh roll in the same, and a web feeding band in frictional engagement with the partially unwound roll and with the fresh roll simultaneously.

12. A device for lifting and changing paper rolls in rotary and other printing machines which print from the roll, comprising in combination, auxiliary bearers for taking up the spindle of the roll to be printed, lifting bearers for taking up a fresh paper roll, a device for ejecting the unwound roll, an electric motor for moving the lifting bearers into the proximity of the auxiliary bearers in order to deposit the spindle of the fresh roll in the same, a web feeding band in frictional engagement with the partially unwound roll and with the fresh roll simultaneously and a compensating drive operatively connected to the spindle of the fresh roll and operating to compensate for the diminishing diameter of the roll as the paper web unwinds and thereby maintain the roll in driving contact with its feeding band.

13. A device for lifting and changing paper rolls in rotary and other printing machines which print from the roll, comprising in combination, auxiliary bearers for taking up the spindle of the roll to be printed, lifting bearers for taking up a fresh paper roll, a device for ejecting the unwound roll, an

- electric motor for moving the lifting bearers into the proximity of the auxiliary bearers in order to deposit the spindle of the fresh roll in the same, a web feeding band in frictional engagement with the partially unwound roll and with the fresh roll simultaneously, an electrically operated automatically compensating drive operatively connected to the spindle of the fresh roll and operating to compensate for the diminishing diameter of the roll as the paper web unwinds and thereby maintain the roll in driving contact with its feeding band, and an electro-magnetically operated clutch mechanism for cutting out the said compensating drive when the motor moving the lifting bearers is in operation and for throwing in the said compensating drive when the motor is cut out.
14. A device for lifting and changing paper rolls in rotary and other printing machines which print from the roll, comprising in combination, auxiliary bearers for taking up the spindle of the roll to be printed, lifting bearers for taking up a fresh paper roll, a device for ejecting the unwound roll, an electric motor for moving the lifting bearers into the proximity of the auxiliary bearers in order to deposit the spindle of the fresh roll in the same, a web feeding band in frictional engagement with the partially unwound roll and with the fresh roll simultaneously and a severing mechanism for severing the unwound web from the rest of the paper on the spindle at a predestined moment.
- In testimony whereof I have signed my name to this specification.
- HARRY PRIESTER,
Executor of Alfred Fallot, deceased.
- 95
15. A device for lifting and changing paper rolls in rotary and other printing machines which print from the roll, comprising in combination, auxiliary bearers for taking up the spindle of the roll to be printed, lifting bearers for taking up a fresh paper roll, a device for ejecting the unwound roll, an electric motor for moving the lifting bearers into the proximity of the auxiliary bearers in order to deposit the spindle of the fresh roll in the same, a web feeding band in frictional engagement with the partially unwound roll and with the fresh roll simultaneously and automatically operating switching means for controlling the operation of the electric motor moving the lifting bearers.
16. A device for lifting and changing paper rolls in rotary and other printing machines which print from the roll, comprising in combination, auxiliary bearers for taking up the spindle of the roll to be printed, lifting bearers for taking up a fresh paper roll, a device for ejecting the unwound roll, an electric motor for moving the lifting bearers into the proximity of the auxiliary bearers in order to deposit the spindle of the fresh roll in the same, a web feeding band in frictional engagement with the partially unwound roll and with the fresh roll simultaneously, switch control levers for cutting out or reversing the rotation of the motor operating the lifting bearers and strikers on the lifting bearers for operating the switch control levers.
17. A device for lifting and changing paper rolls in rotary and other printing machines which print from the roll, comprising in combination, auxiliary bearers for taking up the spindle of the roll to be printed, lifting bearers for taking up a fresh paper roll, a device for ejecting the unwound roll, an electric motor for moving the lifting bearers into the proximity of the auxiliary bearers in order to deposit the spindle of the fresh roll in the same, a web feeding band in frictional engagement with the partially unwound roll and with the fresh roll simultaneously and a severing mechanism for severing the unwound web from the rest of the paper on the spindle at a predestined moment.
